UNITED STATES PATENT OFFICE.

WILLIAM F. CROUCH, OF SEATTLE, WASHINGTON.

BATTERY TERMINAL.

Application filed January 12, 1921. Serial No. 436,713.

To all whom it may concern:

Be it known that I, WILLIAM F. CROUCH, a citizen of the United States of America, and resident of the city of Seattle, in the 5 county of King and State of Washington, have invented certain new and useful Improvements in Battery Terminals, of which the following is a specification.

My invention relates to electrical connectors or terminals particularly for use 10 with storage batteries. It includes a terminal member which may be employed with any of the commonly used storage battery terminals.

One object of my invention is to provide a connector for such use which will 15 form perfect contact between the two elements of the connector and which will maintain this contact under all working conditions.

Another object of my invention is to provide means whereby the two members which 20 are in electrical contact may be sealed to prevent corrosion by the introduction of 25 gases or of acids.

My invention comprises those novel parts and combinations thereof which are shown in the accompanying drawings, described in the specification, and particularly defined 30 by the claims terminating the same.

In the accompanying drawings I have shown my invention in the form which is now preferred by me.

Figure 1 is an elevation of my connector, 35 a portion being shown in section and disconnected.

Figure 2 is a section through the connector, parts being shown connected.

Figure 3 is an end elevation of one member 40 of my connector, the cap and washer portions being omitted, and the attached conductor shown in section.

In the ordinary use of storage batteries 45 where a heavy current is employed under low voltage, contacts in connectors and the like must be practically perfect to insure good or even workable results. In such connectors the common practice is to employ a member formed of an alloy composed principally of lead, and the terminal 50 member of a harder material such as brass, coated in some instances with a film of lead, which fits within a socket of the first member to make contact between the two. The 55 brass used in these members corrodes when exposed to the air, to the acids contained

in the battery, or if exposed to salt water as when used for marine work. Corrosion of the surface of the brass member breaks contact between it and the lead member and 60 renders the battery useless until the corroded surface is cleansed. With the usual type of connectors the two contacting members cannot ordinarily be forced tightly enough into engagement to prevent the 65 introduction of air film or of acids or, when they are occasionally closely united, they are liable to become disunited by reason of the slight rotational movements caused by 70 jarring, under working conditions. Moreover, the brass member is not, in such connectors, securely sealed against corrosion. It is the elimination of the possibilities of 75 corrosion to which my invention is directed.

The member 1, which forms a part of 75 my connector, may be formed of the lead alloy or of other suitable material. It is provided with a socket 10 which is adapted to fit upon a terminal post of a storage battery and to be lead-burned thereon as is 80 the usual practice. The member 1 has also a socket 11 which is tapered to receive a tapered terminal member 2, this being the brass member of the connector, or its equivalent. A lead wire 3 is secured to the terminal member 2 in some suitable manner, as by securing it within a socket 20 therein. The member 2 may have at its smaller end 85 a threaded recess 21, this being adapted for engagement by a bolt, which is not shown in the present drawings but which is used in connection with other types of socketed members to draw the tapered terminal 2 into place. It may be seen that my tapered terminal 2 is capable of use with all of the 90 commonly used tapered socket terminal connectors.

The members 1 and 2 are provided with 95 interengaging means when the terminal 2 is seated within the socket 11 which co-operate to prevent relative rotational movement therebetween. The means which I have shown and which I now prefer consist of a head 22 forming a part of the terminal 2 and of polygonal shape, which 100 is adapted to fit within a recess 12 in the end of the member 1 and surrounding the tapered socket 11. Means are provided for forcing the terminal 2 into its socket 11 and thus to cause the head 22 to be forced firmly 105 into its recess 12. These means may consist of the cap 4 threaded at 41 upon the 110

member 1. The cap 4 surrounds the lead wire 3 and is provided with means for engaging the head of the terminal 2 to force it inward. It is apparent that other means 5 for forcing the terminal 2 into its socket may be employed, such means being common in the art. With the polygonal head 22 of the terminal fitted in the recess 12, relative rotational movement between the 10 member 2 and the socketed member 1 is prevented and thus the breaking of contact between the two members caused by such relative movement is prevented.

As a seal to prevent further the introduction 15 of corrosive substances between the members 1 and 2, I provide a washer 5 of malleable and non-corrosive material, such as pure lead, which surrounds the lead wire 3 and which is adapted to fit upon or to cover 20 the outer end of the terminal 2. Means are provided for forcing this washer 5 down upon the member 2 and into close association with the lead wire 3. To this end I form the washer 5 with a tapered surface 25 and extend the cap 4 outward to form a boss 40 having a tapered inner surface adapted to engage the tapered surface of the washer 5. As the cap is screwed into place the tapered boss 40 presses the washer 30 5 downward upon the head of the terminal 2 and forces it closely about the lead wire, thus completing the sealing of the terminal 2.

It is desirable to hold the washer 5 35 against turning while it is being forced or clamped in place. I have shown a head 23 of polygonal shape, shown herein as square and upstanding from the head 22 of the terminal 2. The washer 5 is provided with a complementary recess which fits over the head 23, the washer and head 23 being thus interengaged to prevent relative rotation therebetween. The terminal head 40 being held against rotation in its socket by 45 the means above described, the washer 5 is also held against rotation and the action of the cap 4 in turning serves only to press it and to crimp it in place about the lead wire and upon the head of the terminal 2. 50 When thus crimped in place it is practically impossible for corrosive substances to reach the contact surface between the terminal 2 and its socket 11.

What I claim as my invention is:

55 1. A battery connector comprising a member having a tapered socket, and having a non-circular recess about the rim of said socket at its large end, a flexible conductor, a plug secured upon the end of said flexible 60 conductor and tapered to fit snugly within said socket, a radial flange about the large end of said plug, said flange being non-circular in shape and adapted to fit within said non-circular recess, when the plug is

seated within the socket, to prevent their 65 relative rotation, and means for forcing said plug into said socket and for holding it there.

2. A storage battery connector comprising 70 a member having a tapered socket, a flexible conductor, a plug secured upon the end of said flexible conductor, and tapered to fit snugly within said socket, means for preventing relative rotation between said plug and socketed member when the plug is 75 seated within the socket, a washer of plastic, non-corrosive material surrounding said flexible conductor, said washer and plug having means interengageable to prevent 80 their relative rotation, and a cap surrounding said flexible conductor and threading upon said socketed member, and bearing upon said washer to force the washer into contact both with the flexible conductor and with the plug, and to force the plug into its socket.

3. A storage battery connector comprising 85 a member having a tapered socket, a flexible conductor, a plug secured upon the end of said flexible conductor and tapered to fit snugly within said socket, a washer of plastic non-corrosive metal surrounding said flexible conductor, a non-circular boss upon the large end of said plug, a corresponding non-circular recess in the adjacent end of the washer engageable with 90 said boss to prevent relative rotation of the washer and plug, and means for forcing said washer about said flexible conductor and against said plug, and said plug into 95 its socket.

4. A storage battery connector comprising 100 a member having a tapered socket, a flexible conductor, a plug secured upon the end of said flexible conductor and fitting within said socket, means interengageable 105 between said socketed member and plug, when the latter is seated within the socket, for preventing their relative rotation, a cap surrounding said flexible conductor 110 and securable upon said socketed member to seat the plug within its socket, an internally coned extension upon said cap extending away from the plug and spaced from the flexible conductor, and a plastic metal washer interposed between the head of said plug, the cap, and the flexible conductor, and engageable by 115 said coned extension to be forced into close association with both the plug and flexible conductor.

5. A storage battery terminal as in claim 4, the plug and washer having means interengageable when forced together to prevent 120 their relative rotation.

Signed at Seattle, King County, Washington this 7th day of January 1921.

WILLIAM F. CROUCH.
